RAILWAY TRACK CLEANER

Edward Shields, El Paso, Tex.

Application September 2, 1933, Serial No. 688,013

1 Claim. (Cl. 15—20)

This invention relates to improvements in railway equipment and pertains particularly to a device for cleaning trackways.

In certain sections of the country railway lines are of necessity required to pass through areas where considerable sand or other loose dirt is found and this is frequently shifted onto the trackways by the wind and is a source of considerable annoyance to occupants of trains passing over the tracks as a result of the dirt and sand being drawn up by the suction created by the train and disseminated through the coaches. In addition considerable damage results to certain moving parts of the engine and coaches by the sand working in between bearing surfaces and it is highly desirable for these reasons that the tracks be kept free of such matter.

The primary object, therefore, of the present invention, is to provide a device for cleaning away from the tracks any sand or other loose dirt which is of a character to be distributed through the air by the violent air currents created by trains passing over the tracks.

Another object of the invention is to provide a mechanism which is designed to be periodically drawn over track lines to thoroughly clear away sand or dirt from the track so that no matter of this character will be present to be sucked up into the mechanism of trains or discharged into passenger cars which may pass over the line.

The invention broadly contemplates the provision of a wheeled structure which traverses the tracks and which carries a hood which lies in close proximity to the tracks and into which fluid under pressure, preferably steam or air, is discharged so as to stir up the dirt immediately surrounding the track to facilitate the ready carrying off of the same through a discharge head or nozzle by means of which the dirt may be discharged to one side of the roadway. This carrying off of the dirt is assisted by the injection of air or steam into the discharge nozzle so as to create a suction within the hood.

A still further object of the invention is to provide a device which may be employed, in addition to the manner above set forth, to remove sand or other debris from the trackway and deposit the same into a receiving carrier, when it is not desired to deposit the material at a side of the roadway.

The invention will be best understood from a consideration of the following detailed description taken in connection with the accompanying drawings forming part of this specification, with

the understanding, however, that the invention is not confined to any strict conformity with the showing of the drawings but may be changed or modified so long as such changes or modifications mark no material departure from the salient features of the invention as expressed in the appended claim.

In the drawings:—

Figure 1 is a vertical longitudinal sectional view through the device embodying the present invention;

Figure 2 is a view in top plan of the same;

Figure 3 is a bottom plan view of the device;

Figure 4 is a sectional view taken substantially upon the line 4—4 of Figure 1;

Figure 5 is a sectional view taken on the line 5—5 of Figure 1.

Referring now more particularly to the drawings wherein like numerals of reference indicate corresponding parts throughout the several views, 20 the numeral 1 indicates generally a portion of a railway track upon which the device is shown mounted. The device embodying the invention comprises a chassis frame or truck 2 mounted upon the flanged wheels 3 by which it is supported over and upon the track 1.

The central portion of the chassis 2 is laterally enlarged to receive between its side rails, which are indicated by the numeral 4, the hood body which is indicated generally by the numeral 5. 30 This hood comprises the top wall 6 which through its major portion is inclined longitudinally of the structure and which has at one end of the structure a horizontal portion 7, the side walls 8 and the front and rear end walls indicated respectively by the numerals 9 and 10. The lower part of the hood is open as illustrated and lies in close proximity to the heads of the rails of the track.

Formed integral with the portion 7 of the top wall of the hood is the upwardly directed outlet spout 11 which is relatively broad at its bottom and tapers to the top terminating in the cylindrical upper end portion 12 which is surrounded at its lower end by the flange 13. This upper end portion 12 of the spout receives a similarly formed end 14 of a nozzle structure 15, the end 14 being right angularly disposed with respect to the major portion of the nozzle so that material which is carried up into the nozzle will be discharged horizontally therefrom. The receiving end of the nozzle rests upon the flange 13 and is rotatable upon the upper end of the spout so that the outlet end of the nozzle may be directed laterally of the

structure as well as longitudinally as it is illustrated.

Extending through the elbow portion of the nozzle 15 and directed longitudinally thereof toward the outlet end is a pipe 16 which has its outlet tip 17 relatively close to the outlet end of the nozzle. The outer end of this pipe is connected with a control valve 18 and in operation has joined thereto a hose 19 which is in turn connected with a suitable source of compressed air or steam, for the purpose hereinafter more fully explained.

In the rear end of the hood there is disposed the downwardly and forwardly inclined baffle wall 20 which at its upper edge connects with the top of the hood adjacent the back of the spout 11 as illustrated in Figure 1. Between the lower edge of this baffle wall 20, which extends the full width of the hood between the side walls 8 thereof, and the forward wall 9, there is mounted a series of 15 ejector units, each of which is indicated as a whole by the numeral 21, and each of which comprises a series of outlet nozzles each of which is indicated by the numeral 22. In the structure here illustrated three of the units 21 are shown and these are disposed transversely of the hood in spaced relation and the end ones have their discharge nozzles directed downwardly and toward the center unit while the center unit has a double 20 row of discharge nozzles each of which is directed downwardly and toward an outside unit. These units are connected at one end by a manifold pipe 23 and this has leading to it the supply pipe 24 which passes downwardly through the top of the structure and at its outer end is provided with a 25 control valve 25 and in addition has connected thereto a flexible supply pipe 26 through which compressed air or steam may be discharged from a suitable source upon the engine drawing the device or in any other suitable location.

40 The units 21 are individually controlled by valves 27 so that any one may be cut out of service if found necessary or desirable. These units 21 are disposed in a plane in close proximity to the lower edge of the hood so that air or steam discharged from the nozzles will have only a short 45 distance to travel before coming in contact with the sand and dirt lying over the trackway.

In order to prevent the material which is disturbed from the air or steam blasts from escaping 50 from beneath the hood, there are provided the curtains 28 which are joined to the lower edges of the side walls 7, the ends wall 9 and the baffle wall 20 which are of sufficient length to pass over

or drag across the ties of the track. The curtains which are connected with the walls 9 and 20 and extend transversely of the track are provided with cut out areas 29 to receive the track rails as illustrated in Figures 4 and 5.

5 From the foregoing description it is believed that it will be obvious that in operation the structure described will be drawn along the track and while in passage there will be injected into the pipes 16 and 24, air under pressure or steam. This 10 air or steam escaping through the nozzles of the units 21 will lift or stir up the dirt and sand so as to raise it within the hood and the air or steam passing through the pipe 16 and escaping through the outlet of the nozzle 15 will create a suction 15 which will draw the raised sand and dirt upwardly and cause it to be discharged through this nozzle. If the device is employed in a train line, the nozzle 15 will be turned to discharge to a side of the track. However, if sand is being removed from 20 the track and it is not desired to discharge the same at a side of the trackway, the cleaning device may be drawn over the track with a flat or open car following and the nozzle 15 will then be directed longitudinally to the rear so that the 25 sand picked up will be discharged into the following car.

Having thus described the invention, what is claimed is:—

An ambulatory structure of the character described, comprising a housing having a forward and a rear end and having an open under side, supporting means for said housing facilitating the movement of the same, an upwardly opening outlet at the top of said housing in close proximity to the rear end, a partition wall extending downwardly and forwardly within the housing from a point at the rear side of the outlet opening to the bottom edge of the open under side of the housing, the lower edge of said partition extending a substantial distance forwardly beyond the outlet opening, a plurality of pipes extending in spaced relation transversely of the housing adjacent the open under side and between the lower edge of said partition and the front end of the housing, 40 means for conducting air or steam under pressure to said pipes, a plurality of nozzles carried by the pipes, the nozzles of one pipe being arranged in downwardly convergent relation with the nozzles of an adjacent pipe, and a discharge nozzle 45 coupled with the outlet opening of the housing.

EDWARD SHIELDS.
